UNITED STATES PATENT OFFICE

148,109

DESIGN FOR A FLASHLIGHT TELEGRAPH KEY

Irving Korrol, New York, N. Y.

Application October 4, 1946, Serial No. 133,739

Term of patent 3½ years

(Cl. D48—24)

To all whom it may concern:

Be it known that I, Irving Korrol, a citizen of the United States, residing in New York, in the county of Manhattan and State of New York, have invented a new, original, and ornamental Design for a Flashlight Telegraph Key, of which the following is a specification, reference being had to the accompanying drawing, forming a part thereof.

In my drawing:

Fig. 1 shows a perspective view of a flashlight telegraph key showing my new design,
Fig. 2 shows a side view thereof.

I claim:

The ornamental design for a flashlight telegraph key, as shown.

IRVING KORROL.
